(57) **CLAIM**

The ornamental design for a soap dispenser, as shown and described.

DESCRIPTION

FIG. 1 is a top, front, right perspective view of a soap dispenser showing our new design;

FIG. 2 is a reduced, exploded top, front, right perspective view thereof;

FIG. 3 is a top view thereof;

FIG. 4 is a right side view thereof, wherein the left side view is a mirror image thereof;

FIG. 5 is a front view thereof;

FIG. 6 is a rear view thereof; and,

FIG. 7 is a bottom view thereof.

The uneven-length broken lines immediately adjacent to the shaded area represent unclaimed boundaries of the design. The even-length broken lines showing the remainder of the soap dispenser are for environmental purposes only and form no part of the claimed design.
